UNITED STATES PATENT OFFICE.

EVAN W. CORNELL, OF ADRIAN, MICHIGAN, ASSIGNOR OF ONE-HALF TO FREDERICK H. KNAPP, OF CHICAGO, ILLINOIS.

GAS-LAMP.

No. 873,663.

Specification of Letters Patent.

Patented Dec. 10, 1907.

Application filed September 6, 1906. Serial No. 333,543.

To all whom it may concern:

Be it known that I, EVAN W. CORNELL, a citizen of the United States, residing at Adrian, in the county of Lenawee and State 5 of Michigan, have invented a new and useful Improvement in Gas-Lamps, of which the following is a specification.

My invention relates particularly to down-draft incandescent gas lamps for use in connection with gas fixtures of various kinds, 10 such as chandeliers and wall brackets.

My primary object is to provide a lamp of the character indicated possessing the characteristics of simplicity and cheapness of construction and operating in an improved manner.

The invention is illustrated in its preferred embodiment in the accompanying drawings, in which—

20 Figure 1 represents a side elevational view of my improved lamp as applied to a chandelier-arm; Fig. 2, a broken sectional view taken in the plane of the paper in Fig. 1; Fig. 3, a broken elevational view taken as indicated at line 3 of Fig. 1; Fig. 4, a broken view taken as indicated at line 4 of Fig. 1; Figs. 5, 6 & 7, sectional views of the burner-tube taken as indicated at the corresponding line of Fig. 2; and Fig. 8, a view looking at 30 the mouth of the burner-tube, as indicated at line 8 of Fig. 2.

In the construction illustrated, A represents a chandelier-arm; and B, my improved gas lamp applied thereto. The lamp comprises 35 a nipple b applied to the chandelier-arm and provided with a gas passage controlled by a needle valve b¹; a burner-tube b² adjustably connected with the member b; a globe-support b³ carried by the member b²; 40 a globe b⁴ depending from said globe-support; a mantle b⁵ depending from the tip of the burner-tube; and a smoke-guard or canopy b⁶ supported on a stem b⁷ rising from the burner-tube b².

45 The nipple b has a base portion b⁸ with a threaded vertical bore screwed on to the upturned extremity of the chandelier-arm, and an inclined portion b⁹, at right angles to which the needle valve b¹ is arranged. The 50 nipple has an inclined passage b¹⁰ and a lateral orifice b¹¹ in alinement with and through

which the gas is directed into the burner-tube. The burner-tube has an inclined portion b¹² which is in axial alinement with the needle valve; and a downturned portion b¹³ supplied with a tip b¹⁴ of peculiar formation. The inclined portion b¹² of the burner-tube is equipped exteriorly with a flange or guard b¹⁵, which preferably is of the rectangular form shown in Fig. 5, and which may be cast 60 integrally with the burner-tube. On the upper side of the inclined portion b¹² of the burner-tube and below the guard b¹⁵ is a socket b¹⁶ which receives the stem b⁷. The inclined portion b⁹ of the nipple b is equipped 65 with lateral perforate lugs b¹⁷ which receive a guide-stud b¹⁸ and the stem of an adjusting screw b¹⁹ projecting from lateral lugs b²⁰ with which the burner-tube is provided at its upper, or base, end. The head of the adjusting 70 screw and a collar b²¹ screwed on to the adjusting screw embrace the corresponding lug b¹⁷ and provide against longitudinal thrust of the screw. The stud b¹⁸ is firmly secured in the corresponding lug b¹⁷, and its lower end 75 moves freely in a guide-perforation b²² with which the corresponding lug b²⁰ is provided. Depending from the base portion of the burner-tube is a slightly curved lug b²⁴ which supports the globe-support b³. The globe-support is preferably formed of a strip of sheet metal bent into ring form, the extremities being connected with the lug b²⁴ by screws b²⁵, as shown in Fig. 3. One extremity is provided with a tenon b²⁶ which fits in a 80 mortise or socket with which the other extremity is provided.

The needle valve b¹ may be of any suitable construction. As shown, it has a threaded shank b²⁷ which works in an internally-threaded perforate boss b²⁸ with which the nipple b is provided. The valve is provided at the base of its conical portion with a collar b²⁹ which is recessed as shown, and which works in the bore b³⁰, serving as a guide for 90 the extremity of the valve. The stem of the valve is equipped with a disk b³¹ equipped peripherally with thin teeth or projections, enabling the valve to be operated without 95 discomfort from heat.

The burner-tube b² is provided just below its angle b³² with opposed lateral lugs b³³ and

with an additional lateral lug b^{34} , the latter having a socket b^{35} . The lugs serve as a support for a mantle-ring b^{36} of well-known construction. The socket b^{35} serves to prevent 5 accidental displacement of the mantle-ring. The tip b^{14} of the burner-tube is externally flanged as shown in Figs. 2 & 7, and the annular end surface of the same is provided with scallops or recesses b^{37} , as shown in Figs. 10 2 & 8. The interior surface of the burner-tip is provided with three triangularly arranged fillets α producing a constricted triangular bore near the end of the tip, the recesses b^{38} of the bore meeting the scallops b^{37} 15 at the tip extremity. This formation of the burner-tip facilitates the spreading of the gas and insures a more complete incandescence of the mantle at its upper or base end. The scallops b^{37} are staggered with relation to 20 the mantle-supporting lugs, so that drafts will be created avoiding the deposition of carbon on said lugs. The burner-tip is preferably supplied with a gauze cone b^{39} which is introduced from the base end of the burner-tube and lodged adjacent to the bend or angle in the tube, the base of the cone engaging 25 an internal annular recess of the burner-tube. The burner-tube is provided near its tip with flattened convergent external surfaces b^{40} , 30 which facilitate the adjustment of the mantle.

The operation of the lamp will be readily understood from the foregoing detailed description. The burner-tube is adjusted bodily with relation to the nipple b by means 35 of the screw b^{19} , leaving a space b^{41} between the base end of the burner-tip and the nipple for the admission of air. Once the burner-tip is adjusted for a given pressure of gas, there is no occasion for further adjustment.

40 The needle valve b^1 is useful for the purpose of keeping open the orifice b^{11} . As the gas is injected into the burner-tube the air is drawn in with it in the usual manner, and the mingled air and gas pass by a short route to the 45 tip of the burner-tube where the ignition occurs. It will be observed that the formation of the burner-tube provides against the subjection of the gas to any great heat before the tip of the burner-tube is reached, thereby 50 obviating objections to constructions of the goose-neck type now in common use. The guard b^{15} serves to prevent the fire from flashing back to the orifice b^{11} , and it serves further to cause the products of combustion 55 to follow the same general direction to the side of the globe which is opposite the chandelier-arm.

Practical operation of the device has shown that perfect combustion may be obtained thereby, and the heat employed in the most economical manner for producing incandescence of the mantle. The burner-tube may be readily formed of cast-iron and

is practically indestructible. The nipple b and the attendant parts, and the globe-support b^3 , which are exposed to view, may be of brass. It will be noted that there are no adjustable parts exposed to intense heat.

The foregoing detailed description has been given for clearness of understanding 70 only, and no undue limitation is to be understood therefrom.

What I regard as new, and desire to secure by Letters Patent, is—

1. The combination of a burner-tube having 75 an inclined base portion and a depending tip portion, a globe support, a globe depending from said support and inclosing the tip portion and a part of the base portion of said burner-tube, and a transverse guard on said inclined base portion extending within the upper portion of said globe.

2. The combination of a nipple having an inclined gas outlet orifice, a burner-tube having 85 an inclined base portion mounted on said nipple in alinement with said orifice and having, also, a depending tip portion forming an obtuse angle with said base portion, a globe support carried by said base portion, a globe depending from said support, and a guard 90 within the upper portion of the globe mounted on said base portion of the burner tube and inclined in a direction opposite the direction of inclination of the base portion of the burner tube.

95 3. The combination of a nipple adapted to be applied to a chandelier-arm and provided with a lateral orifice, a valve connected with said nipple and controlling said lateral orifice, and a bodily-movable burner-tube adjustably supported on said nipple and having its base portion separated from the nipple by an air-admission space, said burner-tube having a depending tip forming an angle with the body portion of the burner tube.

100 4. The combination of a nipple having a vertical threaded bore and an inclined portion provided with a lateral inclined gas orifice, and a bodily-movable burner-tube adjustably carried by said inclined portion 110 and having an inclined base portion presented to said gas orifice and a depending burner-tip forming an obtuse angle with said inclined portion.

115 5. The combination of nipple having a base portion provided with a vertical bore and an inclined portion carried thereby having a gas passage provided with a lateral orifice, a burner-tube having an inclined base portion adjustably connected with the inclined portion of said nipple and equipped with a depending burner-tip, and an external inclined guard carried by the inclined portion of the burner-tube and extending transversely thereof.

120 6. The combination of a nipple provided

with a lateral gas orifice, a burner-tube having its base portion presented to said orifice and equipped with a burner-tip at an angle to the base portion, a guide connecting the base portion of the burner-tube with said nipple, and an adjusting screw connecting the base portion of the burner tube with said nipple.

5 7. A burner-tube having a tip provided

with external lugs and having a bore terminating in an angular orifice whose recesses 10 are staggered with relation to said lugs.

EVAN W. CORNELL.
